(57) **CLAIM**

The ornamental design for a product packaging, as shown and described.

DESCRIPTION

FIG. 1 is a bottom view of the product packaging.

FIG. 2 is a side view thereof.

FIG. 3 is a front view thereof.

FIG. 4 is the other side view thereof.

FIG. 5 is a rear view thereof.

FIG. 6 is a top view thereof.

FIG. 7 is a front and top side perspective view thereof.

FIG. 8 is rear and side bottom perspective view thereof; and, FIG. 9 is an unfolded view of the product packaging of FIG. 1.

The dashed lines in FIG. 9 represent fold lines and are part of the claimed design.
